CLAIM

The ornamental design for a golf club ferrule, as shown and described.

DESCRIPTION

FIG. 1 is a top perspective view of a golf club ferrule according to a first embodiment;

FIG. 2 is a bottom perspective view of the golf club ferrule of FIG. 1;

FIG. 3 is a front elevational view of the golf club ferrule of FIG. 1;

FIG. 4 is a rear elevational view of the golf club ferrule of FIG. 1;

FIG. 5 is a left side view of the golf club ferrule of FIG. 1;

FIG. 6 is a right side view of the golf club ferrule of FIG. 1;

FIG. 7 is a top view of the golf club ferrule of FIG. 1; and,

FIG. 8 is a bottom view of the golf club ferrule of FIG. 1. The broken lines shown on the drawings form no part of the claimed design.

1 Claim, 4 Drawing Sheets
